HAND WARPING DEVICE FOR HAND LOOMS

Peter Florjancic and Emil Boral, Zurich, Switzerland; assignors to Max Bucher, Zurich, Switzerland

Application December 7, 1944, Serial No. 567,059;
In Switzerland August 6, 1943

2 Claims. (Cl. 28—26)

1

This invention relates to hand looms...

The hand loom according to the present invention is distinguished by auxiliary means in the form of supporting means for thread supply spools to be donned, said supporting means being arranged on a member which is associated with the reed and serves for guiding threads that are intended to be unwound from said spools and guided through the reed, and by bearing means which serve for mounting the warp beam therein and are provided with a drive for rotating the warp beam for the purpose of winding said threads on said beam.

This arrangement permits of winding threads on the warp beam in the loom in the required manner for said threads then to be used for forming the warp of the loom. Due to this arrangement the hand loom weaver is enabled to perform prior to the weaving the necessary beaming operation, that is, beaming direct on to the weaver's beam himself, so that the field of operation of the hand loom weaver is accordingly enlarged, which is highly appreciated particularly in regard to home work; this kind of working being important from the point of view of national economy especially in regions having little or no textile industry at all. The warp threads to be delivered by the thread supply spools may be subjected to a pretreatment for influencing its properties to any required or suitable extent.

The subject matter of the present invention is illustrated partly schematically in the accompanying drawings in connection with a dismountable hand loom, in which:

Fig. 1 shows an elevation of the hand loom;

Fig. 2 is a part top plan view of Fig. 1;

Fig. 3 is a view of the upper part of the loom frame including the guiding member and the warp beam, said two parts appearing in section;

Fig. 4 is a top plan view of Fig. 3;

Fig. 5 is a perspective view indicating the course of the thread being beamed;

Fig. 6 is a perspective view representing the bearing means for the mounting of the warp beam;

Fig. 7 is a larger scale sectional view of a support on the loom frame with the shuttle race detachably secured thereto;

Fig. 8 is a perspective view of a rack which is assembled from loom frame posts and serves for producing carpets by knotting work;

Fig. 9 is a sectional view of parts of said rack;

Fig. 10 shows a longitudinal section of a modified guide member in the form of an extensible comb;

2

Fig. 11 is a view of an arrangement including the extensible comb and other parts required for effecting the beaming of the warp, and

Fig. 12 is a larger scale view of a thread brake in operative position.

As shown in Figs. 1 and 2, in the frame of the loom on two lower rods 1 and 2 extending parallel to each other, two carriers 3 which extend transversely of said rods are supported and have arranged thereon a pivot 5 by means of bearings 4. Four lifting cams 6, 7, 8 and 9, which are united into a block, are fixedly mounted on the shaft 5 for common rotation therewith. With each of the four lifting cams 6 to 9 which have a form similar to a quadrant and are all relatively offset at angles at the center of 90° individual actuating rods 11 to 14 respectively cooperate.

The four actuating rods 11 to 14 provided are swingably mounted at one of their ends on a bolt 15 which is arranged in common with said rods and is secured to both carriers 3. The other ends of said rods are each connected by means of a cord drive 16 with one of four shafts 17 to 20 respectively, in a known manner.

Each of said shafts 17 to 20 which, in a known manner, carry the healds by means of two shaft staves, carries on both of its ends a stationary supporting bar for interengagement with a tubular guide, the lower end of which is closed and which houses a helical spring, whereby the two shafts are resiliently supported. The four guide tubes 24 that are situated at adjacent ends of the shafts 17 to 20 are welded together with a common connecting rod 26 of the loom frame. By 27 the shuttle race of the slay is referred to, which is swingably arranged on lower connecting rods 44 of the loom frame by means of slay swords 28, in a manner known per se, and carries the reed 29. The numerals 30 and 31 denote warp threads arriving from the warp beam 32. The cloth beam is referred to as 33.

On the shaft 5 carrying the cam discs 6 to 9 is further arranged a sprocket 34 the rim of which is secured to a hub portion which is keyed to the pivot 5. Between the two wheel parts balls are included so as to form together with said parts a unidirectional coupling, that is, a free wheel hub arrangement. About the rim of the sprocket 34 passes a chain 31 one end of which is attached to a tension spring 38 and the other to a two-armed pedal lever 39. The other end of the tension spring 38 is hooked to a hook 40 which is fastened on one of the carriers 3. The pedal lever 39 is mounted on the rod 2 and is provided on its lower side with a set screw 41 which

serves as a stop for limiting the throw of the pedal lever 39 by hitting the floor as this lever moves in the corresponding direction. A set screw 42 arranged on one of the carriers 3 serves as an abutment for limiting the throw of the pedal lever 39 in the other direction of movement.

By depressing the pedal lever 39 in the direction of the arrow shown in Fig. 1 the pivot 5 is accordingly turned by action of the chain 37 and consequent stressing of the spring 38, in consequence whereof, for example, the shaft associated with the cam disc 6 is moved downward against spring influence on actuation of said cam. Relieving of the pressure exerted on the pedal lever 39 results in restoring said lever into position of rest under the influence of the tension spring 38.

When the pedal lever 39 is depressed anew the cam disc 8 and thus the cam disc 7 and eventually also the cam disc 9 is rendered effective, so as individually to control the respective shaft, whereupon the cycle of operations is repeated. As the individual discs 6 or 7, 8, 9 respectively are rendered inoperative the associated shafts return into their upper positions by influence of their spring bias.

The pivot 5 has performed one revolution after having been controlled four times. If a lesser or greater number of cam discs is provided the throw of the pedal lever 39 is accordingly adjusted to greater or smaller range. Naturally, the angular ranges of the cam discs about the pivot 5, that is, said ranges of the cam discs relatively to each other, may be adjustable. The point at which the tension spring 38 is attached to the loom frame may, if desired, be adjustable, for example by means of a sliding member.

The possibility of moving all of the shafts or groups of shafts as a whole through the intermediary of a single pedal lever simplifies the work of the attendant person to a great extent compared with the conventional mode of using both feet for the pedal lever control so that in the event that more than two pedal levers are provided the lever control even requires the feet to be dislocated. The heald shaft motion according to the present invention has the effect above all to relieve the attendant person so that said person is enabled to attend to the weaving operation proper with more concentration of mind and economy of physical strength in consequence whereof the efficiency of weaving is increased.

The lower rod 1 serving for carrying the heald shaft motion interconnects two corner posts 45, 46 of the loom frame. An upper connecting rod 47 serves the same purpose. In a similar manner the further corner posts 48, 49 are united by means of a lower and an upper connecting rod 50 and 51 respectively. Transversely of these connecting rods extend the upper and the lower connecting rods 26 and 44 respectively which interconnect the corner posts 45 and 48. In a similar manner the two corner posts 46 and 49 are interconnected by means of an upper and a lower connecting rod. The said eight connecting rods are in form of tubes into each end of which an extension bolt 52 is inserted and held by a cotter pin 53 extending through transverse openings in said tubes and bolts. Each extension bolt 52 protrudes through a cross bore provided in the respective corner post of the loom frame. A nut 54 screwed to the free end of the extension bolt 52 serves for engagement with the corresponding corner post.

By detaching the described connections the

four corner posts 45, 46, 48 and 49 can be isolated. The two carriers 3 being correlated to the shaft motion and which are pushed on the lower connecting rod 1 by means of forked ends can also be detached from said rod on the removal of cotter pins 55 as well as detached in a similar manner from the rod 2 on the removal of cotter pins 56. This rod 2 can in turn be retracted from engagement with forked bearing portions on the rods 44 on the removal of cotter pins 57. Also the connecting bolts on the swords 28 of the slay 27 can be removed from engagement with the rods 44 for the purpose of detaching the connection between the slay 27 and the rods 44.

In consequence thereof the loom frame can be dismounted so that the corner posts 45, 46, 48 and 49 form individual parts. The same applies to all the connecting rods mentioned above. Due to this provision the loom can be stored away during the time of unuse with relatively small space requirement. This is obviously also of great advantage for the transportation of the loom. For the same purpose the shafts 17 to 20 can be detached from the guide tubes 24. The swords 28 of the slay can be fastened to the shuttle race 27 in detachable manner so that the slay can in turn be separated into three parts. Also the reed 29 is detachably connected to the shuttle race 27 and the shaft motion itself is also separable into several parts.

As shown in Figs. 3 and 4 several carrier bars 58 are mounted on the upper connecting rod 47 by means of forked connecting elements so that said bars can be dismounted on the removal of cotter pins 59 also. The carrier bars 58 are each equipped with a row of bolts for the reception of thread supply spools to be donned thereon. With each bolt a thread guide 61 is associated the thread eyelets of which only are shown in Fig. 4. The threads unwinding from the spools 60 are leaded in a group through the reed 29 being connected with the shuttle race 27 of the slay in order to constitute the warp. These threads then pass about the rounded guide surface of a lower attachment member 62 which is detachably secured to the part 27, whereupon the thread group A is threaded through the reed 29 at another reed portion, as shown in Figs. 4 and 5 and is then placed on the warp beam 32 and fastened by means of its end portion to said beam through the intermediary of, for example, a rail which is depressibly arranged in the beam circumference. For the work then to be carried out the shuttle race 27 of the slay has been detachably secured to the corner posts 48, 49 of the loom frame by screw means.

The warp beam 32 is mounted in axle stubs 63, 66 sustained by shanks 64 of a supporting stirrup which is displaceably guided in an upper and a lower guide groove provided in the shuttle race 27 by means of two cross members 65. The axle stub 66 serving as a mounting for the warp beam 32 is in form of a screw spindle which can be turned by a removable hand crank 66' on the square end portion of said spindle. In turning this crank the axle stub 66 shifts axially in a bearing sleeve 67 which is provided on the associated stirrup shank 64, thereby moving along the warp beam 32.

In consequence thereof a winding B of substantially frusto-conical shape is built up on the warp beam 32 by the group of threads A in course of being wound on. After the diameter of this winding has reached a certain extent the thread 75 is severed, whereupon a second similar winding

is produced in similar manner at the side of the first winding and so forth until as many threads have been applied to the warp beam as required. Each time after a thread winding has been produced on the warp beam 32 this beam is axially shifted to the required amount by accordingly shifting the supporting stirrup 64, 65 longitudinally of the shuttle race 27, so that the fresh winding to be effected is placed collaterally of the previously produced winding exactly as required. The warp beam 32 is thus conically increased commensurate with the frusto-conical shape of the windings at that beam end at which the winding operation for producing thread windings has begun, whereby to the first winding an appropriate bearing area on the warp beam has been given. The first winding is then overlain by the second winding on that side which has been left free in performing the former winding and so forth; so that the windings hold each other, that is mutually, in position on the warp beam, to some extent. After the warp beam 32 has been equipped with the warp threads to be used for the weaving in the manner described this beam is removed from the supporting stirrup 64, 65 and is mounted in the bearings provided for the warp beam on the two corner posts 45, 46 of the loom. Thereupon, the supporting stirrup 64, 65 is retracted from the shuttle race 27 and said race 27 is joined with the swords 28 after the attachment 62 has been removed by which means the slay is assembled again. The threads applied to the warp beam 32 are then threaded through the healds of the heald shafts 17 to 20 and through the reed 29 in the manner prescribed, thereby to put the loom in condition for operation.

In order to provide for the shuttle race 27 to be detachably connected to the two corner posts 48, 49 of the loom frame, on both ends of the shuttle race 27 a bolt 69 is fastened by means of a cotter pin 68, as shown in Fig. 7, for the reception of which a cross bore is arranged in the respective corner posts 48 and 49. A nut 70 screwed to the connecting bolt 69 permits of tightening the bolt 69 so as to firmly secure the shuttle race 27 to the said corner posts.

From the explanations given above it follows without any further comment that the described loom is reduced in weight to a relatively great extent, particularly due to the employment of connecting tubes. Further it will be seen that the dismounting and assembling of the loom can be effected without difficulty so as to be easily performable. The swords 28 of the slay are preferably made of pipe material so as to keep down the weight of the slay and permitting of easily moving the slay back and forth.

The four corner posts 45, 46, 48 and 49 provided for forming the loom frame are joined to each other in pairs as shown in Fig. 8 to which end in the plane end faces of the corner posts bores for the reception of pegs 71 are provided. Consequently, pairs of posts 45, 46 and 48, 49 of corresponding lengths are formed the rounded off ends of the parts 45, 48 of which are inserted in corresponding recesses in two base pieces 72 and are secured to said pieces 72 in vertical position by tap bolts 73. The connection between said parts and the base pieces is strongly stiffened by braces 74 which are detachably fastened to the upper parts 48, 49. Since the lower and upper parts of the two posts 45, 46 and 48, 49 are interconnected by connecting rods 1 and 47 respectively a rigid framewise standard is thus obtained. In said standard a lower roller 75 and

an upper roller 76 are accommodated whereby a device is formed which serves for producing carpets by knot-work. To this end the rollers 75 and 76 are instrumental by receiving the longitudinal threads to be used as indicated in chain-dotted lines. The rack described can be dismounted again very easily, as will be readily seen.

As shown in Figs. 2 and 4 the corner posts of the loom are made from three plies of boards, which is not visible in Fig. 8. Naturally these corner posts can consist of an integral piece as well.

Due to the fact that the slay is supported or mounted at its bottom portion and further that upper mounts are avoided a loom which is devoid of such mounts and has inherent advantages typical for this kind of looms is obtained.

For the purpose of facilitating the leasing of threads, that is, the beaming work the employment of an extensible lease reed of the kind shown in Figs. 10 to 12 as a guide means for the threads to be wound off of the thread supply spools and wound on the warp beam lends itself as of particular advantage.

As shown in Fig. 11, an extensible lease reed 80, lease rods 81, 82, a thread brake 83 and a reed 84 are successively arranged with the lease reed in next in advance of the warp beam 32 if considered with respect to the direction of movement of the threads arriving from the thread supply spools via thread guides 85. The parts 80 to 84 are advantageously supported by a common mounting (not shown) which is adapted to be detachably secured to the loom frame. In this way the parts 80 to 84 form together with their supporting means a self-contained accessory which can be attached to the loom as a unit and removed from the loom again after use, as required.

The extensible reed is provided with two head pieces 86, 87 which are rigidly interconnected by two tubes 88, 89 that are fitted into two eyes of said pieces. In each of these two tubes 88, 89 being each provided with a longitudinal slot 90 a spindle 91 or 92 each carrying a right hand thread 93 and a left hand thread 94 is accommodated. On each thread of both of said spindles 91, 92 a nut 95 is arranged which interengages by means of a projection 96 with the longitudinal slot 90 of the respective tube 88 or 89 and is thus prevented from rotating. On the two nuts 95 carried by the same spindle 91 or 92 abuts by means of the adjacent end a helical spring 97 or 98 both of which surround the respective spindle and are maintained stressed continually.

In the helical springs 97, 98 the dents 99 of the reed are anchored by means of eyelets in such a number as to allow of dividing the dents uniformly to the convolutions of the helical springs as shown in Fig. 1. On the end of the screw spindle 92 projecting beyond the head piece 86 a round adjusting disc 100 is fastened with the toothed rim of which cooperates a spring locking arm 101 which in turn is fastened to the head piece 86. In an all around closed chamber 102 of the head piece 86 a chain drive 103 is provided which positively operatively interconnects the two screw spindles 91, 92.

The threads payed out by the supply spools are threaded through between the dents 99 of the extensible lease reed in the required manner. The division of the dents 99 can be adjusted within the limits likely to arise in actual practice dependent upon requirements. This is

effected by means of the rotatable adjusting disc 100 which can be controlled by hand against the resistance opposed thereto by the locking arm 101 which secures the disc 100 in each position of adjustment.

In turning the setting disc 100 in one or the other direction the two screw spindles 91, 92 are correspondingly rotated and the screw nuts 95 accordingly displaced towards or away from each other. Consequently the stressing of the helical springs 91 is increased or decreased as the case may be so that the dents 99 being guided in the longitudinal slots 90 of the respective tubes 88 or 89 are moved towards or away from each other accordingly and the dent division is correspondingly decreased or increased. The nut 95 is provided with a point 104 for cooperation with a division 105 for continually visibly indicating the length of division of the dents 99 as set.

Between the lease reed 84 and the lease rod 82 being instrumental in forming the lease the warp threads pass through the thread brake 83. This brake is provided with two parallel round bars 106 which are interconnected at both of their ends by a separate terminal plate 107. The bars 106 form with the plates 107 a frame which is rotatably adjustably arranged by means of pivot pins 108 one of which is centrally arranged on either terminal plate 107. Each of the two pins 108, which are coaxially arranged, is received in a bearing (not shown), these bearings being provided on the supporting means mentioned in the opening paragraph.

As shown in Fig. 11, the frame 106, 107 the angular position of which is adjustable by means of an auxiliary device (not shown) is in inoperative position so that the warp threads can freely pass between the two relatively opposed round bars 106. If the frame 106, 107 is rotated in the direction of the arrow shown to the required extent the round bars 106 contact with the warp threads so that these threads are tensioned more and more as the said frame keeps on rotating and their movement is eventually braked by action of the round bars 106. The braking frame 106, 107 can, for example, be moved into the position shown in Fig. 12, in which the warp threads contact with the round bars 106 along a stretch which is somewhat greater than half the circumferential length of said bars.

The accessories described for putting the warp threads in condition of use are not only of simple construction but can also be handled in convenient manner.

We claim:

1. In apparatus for performing warping operations, four corner posts forming a frame, means releasably connecting the posts together whereby the frame is collapsible, a support for warping spools mounted on said frame, a warp beam, one end portion of said beam being in the form of a screw threaded rod, a warp beam support on the frame, means engaging the screw threads of said rod, and means for rotating said rod and warp beam to wind on warp threads and to provide relative axial motion between said beam and the spool support.

2. In apparatus for performing warping operations four corner posts forming a frame, means releasably connecting the posts together whereby the frame is collapsible, a support for warping spools mounted on said frame, a warp beam, a warp beam support on the frame, means for rotating and axially moving the warp beam relative to the spool support, a slay, attachment means provided on the frame at predetermined positions, a shuttle race, releasably attached to the slay and having attachment means for cooperating with the attachment means on the frame, whereby the shuttle race may be selectively secured at said different positions and whereby the shuttle race may be moved to position for guiding the thread during a warp winding operation.

PETER FLORJANCIC.
